UNITED STATES PATENT OFFICE

WILLIAM V. SEIFERT, OF DENVER, COLORADO

MUD PUMP

Application filed September 3, 1926. Serial No. 133,485.

This invention relates to pumps and its primary object is to provide a lifting pump particularly adapted for drawing muddy liquids from wells and other sources. It is a distinctive feature of the invention that the turbid liquid passes through the pump without coming in contact with any part of the operating mechanism.

Another feature of the invention resides in the provision of check valves which by the absence of sliding parts are not affected by the abrasive action of grit and sand carried by the liquid drawn through the valves, and still another aim of the invention is to provide in a pump of the above described character floating pistons which separate the liquid from the operating mechanism of the pump and are instrumental in drawing the liquid from its source and impelling it to the point of discharge.

Other objects of the invention reside in details of construction and novel arrangements and combinations of parts as will be fully disclosed in the course of the following description.

In the accompanying drawings, in the several views of which like parts are similarly designated by numerical reference characters,

Figure 1, represents a partially sectional plan view of the pump,

Figure 2, a vertical section taken on the line 2-2 in Figure 1,

Figure 3, an enlarged sectional view of one of the floating pistons of the pump mechanism, in its displacement chamber,

Figure 4, an end-elevation of the pump, looking in the direction of the arrow A in Figure 1,

Figure 5, a vertical transverse section in the planes indicated by the line 3-3 in Figure 2,

Figure 6, a horizontal section along the line 6-6 Figure 4, and

Figure 7, an enlarged and fragmentary sectional view of one of the check-valves which control the passage of displaced liquid to and from the pump.

The pump illustrated in the drawings comprises two units which operate in unison to draw the liquid from its source in alternate movements and impel it to a common point of

delivery. Each unit comprises a horizontal cylinder 5 connected at its ends with two vertical displacement chambers 6 formed adjoining in the housing of the pump, with their lower ends in communication with the ingress-opening 7 and the egress-opening 8 of the same.

Each displacement chamber has two ports 9 and 10 separated by a series of check valves 12, the construction of which will hereinafter be described. The lower port 10 of each displacement chamber is connected with the ingress-opening by a passage 13 and when, as in the construction shown in the drawings, the pump comprises two units, the four displacement chambers open into the one passage as shown in Figure 6. The ports 9 of the displacement chambers above the valves 12, are connected by ducts 14 with a passage 15 in the upper portion of the pump housing, which communicates with the egress-opening by a downwardly extending duct 16 as best shown in Figure 5.

The connection between the ducts and the passage is controlled by check-valves 17 similar in construction to those which control the connection between the lower ends of the displacement chambers and the ingress opening.

The four displacement chambers of the duplex construction illustrated in the drawings, have their respective ports 6 in connection with one and the same passage 15 which as stated before communicates with the single egress-opening 8.

Pistons 18 fitted for reciprocation in the cylinders 5 of the two pump-units, are fastened to rods 19 which extend through stuffing boxes 20, for their connection with sliding cross heads 21. The cross heads are cylindrical and move in correspondingly formed slide ways 22 which at their ends connect with the heads of the respective cylinders 5 and with a crank-case 23.

A shaft 24 mounted in bearings 25 in the crank case 23 has two crank disks 26 the wrists of which are connected with the cross-heads of the two pump units by means of rods 27. The shaft carries between its bearings, a worm wheel 28 which meshes with a worm 29 likewise enclosed in the crank-case. The worm is

5 mounted at the end of a shaft 30 extending through a packed opening of the crank case and connected by a coupling 31 with the rotor of an electric motor 32 which for convenience may be supported on the base 33 of the pump housing.

10 The displacement chambers are lined with bushings 34 for the reciprocating movement of floating pistons 35. These pistons are preferably made, as illustrated in Figure 3, of two hollow cylindrical boxes 36 provided with central tubular openings for their connection by coupling bolts 37. Clamped between the boxes is a disk 38 of felt or other suitable material and at opposite sides of this disk are leather cups 39 which extend around the boxes for engagement with the bushings of the displacement chambers. The felt disk and the leather cups cooperate to maintain the pistons 20 in fluid-tight contact with the walls of the displacement chambers, while permitting of the upward and downward movement of the pistons in the operation of the pump.

25 The check-valves 12 and 17 hereinbefore referred to may be of any suitable construction but I prefer for the purpose of the present invention, the form and arrangement illustrated in the drawings.

30 Each valve-element in each of the displacement chambers or in each of the discharge-ducts is composed of a number of concentric members separated from each other by circular partitions 40. The lower portions of the partitions are beveled to provide the 35 valve-seats 47.

35 The valve-members are each composed of an annular sack 41 of leather or other suitable material containing a body of mercury 42 and fastened by means of bolts 43 upon a metal retaining ring 44. A rubber band 45 in a recess at the upper edge of the ring aids in maintaining a fluid-tight contact with the valve seat when the valve is in its closed position, and metal washers 46 which if so desired may be replaced by a continuous strap, are placed inside the bag for engagement with the heads of the bolts.

40 The upper portion of the bags is of ample fulness to permit of its contraction by suction in the displacement chambers. When this contraction takes place the sides of the bags are drawn away from the beveled valve-seats 47 and the lower portion is lifted sufficiently to permit of the passage of the liquid.

45 After the suction is discontinued and the valves are subjected to pressure, the leather bags are under the influence of the weight of their mercury contents, pressed back against the valve-seats with little or no sliding movement and the weight of the mercury together with the fluid pressure above the valves, maintains a fluid-tight contact of the valves with their respective seats. It will be noted that by eliminating sliding movement of the 60 valves, their wear by grit or sand in the dis-

75 placed liquid is reduced to the minimum, it being understood that the slight up and downward movement of the lower portion of the valve is negligible and that whatever wear may be caused by such movement on the metal retaining ring, does not affect the water-tight condition of the valve, which is entirely dependent on the contact of the sides of the bag with the converging annular seats 47.

75 In the operation of the pump, the cylinder of each unit and the spaces of the respective displacement chambers above the float-pistons are filled with a fluid body preferably oil or other similar substance and the 80 crank case and the cylindrical slide ways connected therewith are likewise supplied with oil for the purpose of lubrication.

85 The cranks of the two pump units are preferably placed at right angles to each other so that the units may operate alternately to draw the water into the common intake passage 13 and impel it to the common delivery passage 15.

90 During reciprocation of the piston of each unit, the oil or other liquid expelled from the respective cylinder at one side of the piston drives the float piston in the respective displacement chamber downwardly while the oil drawn into the cylinder at the 95 opposite side of the piston produces a partial vacuum which causes the float-piston in the other displacement chamber to be drawn upwardly. The upward movement of the last mentioned float piston opens the check-valves at the lower end of the respective displacement chamber with the result that the liquid in the source connected with the ingress opening is drawn through said opening into the passage 13 and thence through the port 10 into the displacement chamber where it follows the movement of the piston 35.

100 In the other displacement chambers which had previously been filled with the liquid drawn through the ingress opening while the piston in the pump cylinder moved in the opposite direction, the liquid is forced downwardly past the closed valves 12 and through the ports 6 whence it passes into the respective ducts 14 and through the respective valve 17 into the passage 15 from where it is delivered to the egress-opening.

110 It will thus be apparent that in the operation of the pump one displacement chamber of each unit is filled while the other discharges its contents, during each stroke of the piston and that the same operation takes place in reverse order in the displacement chambers of the other unit. The pump thus 115 delivers a continuous stream of water and owing to the readily apparent fact that the displaced liquid can not come in contact with the operating mechanism of the pump, the apparatus is particularly adapted to draw 120 125 130

muddy waters from wells and other sources of supply.

The provision of contracting valves which engage their seat with little or no sliding motion as hereinbefore explained adds to the life of the pump and permits of its operation during an extensive period of time without repair or replacement of parts.

It is to be understood that the pump as shown and described is subject to variations in details of construction and in the arrangement of its parts without departing from the spirit or scope of the invention.

Having thus described my invention, what I claim and desire to secure by Letters Patent is:—

1. In a pump having an ingress port and an egress port, a cylinder, a piston in the cylinder, a displacement cylinder connected with the first-mentioned cylinder, the displacement cylinder being in connection with the ingress and egress ports of the pump, a floating piston in the displacement cylinder, a fluid body between the first-mentioned piston and the floating piston, and a check valve in the displacement cylinder, controlling the flow of liquid through the ingress port.

2. In a pump having an ingress port and an egress port, a cylinder, a piston in the cylinder, a displacement cylinder connected with the first-mentioned cylinder, the displacement cylinder being in connection with the ingress and egress ports of the pump, and having a normally closed opening at the bottom thereof, a floating piston in the displacement cylinder, a fluid body between the first-mentioned piston and the floating piston, and a check-valve in the displacement cylinder controlling the flow of liquid through the ingress port.

3. In a pump having an ingress port and an egress port, a cylinder, a piston in the cylinder, a displacement cylinder connected with the first-mentioned cylinder, the displacement cylinder being in connection with the ingress and egress ports of the pump, and having a normally closed opening at the bottom thereof, a floating piston in the displacement cylinder, a fluid body between the first-mentioned piston and the floating piston, and a check-valve unit in the displacement cylinder controlling the flow of liquid through the ingress port, the floating piston and check-valve unit being removable through said opening.

4. In a pump having an ingress port and an egress port, a cylinder, a piston in the cylinder, a displacement cylinder connected with the first-mentioned cylinder, the displacement cylinder being in connection with the ingress and egress ports of the pump, a reciprocating means in the displacement cylinder adapted to follow the movements of the piston, a fluid between the piston and the reciprocating means, and a valve controlling

the ingress port and comprising a housing having a valve seat tapering to a reduced opening and a check valve on the seat controlling the flow through the reduced opening.

5. In a pump having an ingress port and an egress port, a cylinder, a piston in the cylinder, a displacement cylinder connected with the first-mentioned cylinder, the displacement cylinder being in connection with the ingress and egress ports of the pump, a reciprocating means in the displacement cylinder adapted to follow the movements of the piston, a fluid body between the piston and the reciprocating means, the displacement cylinder having a normally closed opening, a valve controlling the ingress port and comprising a housing having a valve seat tapering to a reduced opening and a check valve on the seat controlling the flow through the reduced opening, the valve housing and valve being removable through said opening.

In testimony whereof I have affixed my signature.

WILLIAM V. SEIFERT.
